RAIL JOINT

Robert Faries, St. Davids, Pa.

Application March 19, 1932. Serial No. 599,925

4 Claims. (Cl. 238—244)

This invention relates to track rail joints wherein the contiguous ends of adjoining rail sections are overlapped, at opposite sides, by joint-bars which are clamped against the rail sections by transverse securing bolts.

The present invention constitutes an improvement upon the rail joint disclosed in a previous application Serial No. 592,264, filed by me on February 11, 1932, which features means for automatically compensating for wear between the heads of the adjoining rail sections and the joint bars immediately adjacent the split or separation of the rail, as well as between the lower corners of the bars and the top faces of the base flanges of said rail sections. Although such wear is occasioned mostly by up and down flexure of the juncture under the weight of passing trains, it is in part due to lateral flexure of the joint bars concurrently induced by side thrust of the wheel flanges of the cars.

My present invention has for its aim to retain all the advantages inherent to my previous improvement and in addition to minimize wear on the rail sections and joint bars due to the latter of the above indicated conditions. As herein-after fully explained, I attain this desideratum through provision of joint bars characterized by longitudinal ribs respectively above and below the level of securing bolts, adapted to bear against the vertical center webs of the adjoining rail sections at the regions of emergence of the said webs with the rail heads and base flanges.

In the attached drawing, Fig. I is a view showing my improved track rail joint in side elevation. Figs. II and III are cross sectional views taken as indicated respectively by the arrows II—II and III—III in Fig. I; and

Fig. IV shows the inside elevation of one of my improved joint bars.

As herein delineated, the track rail joint of my invention comprises a pair of joint bars 5 which uniformly overlap the line of separation or split 6 between the contiguous ends of the adjoining rail sections 7, 8, and which are cross sectionally configured, as shown in Figs. II and III, to fit the hollows at opposite sides of the rail. For the greater portion of their lengths the upper and lower edges 9 and 10 of the bars 5 respectively contact with the sloping under faces 12 of the rail heads 13 and the sloping top surfaces 14 of the rail base flanges 15, also as shown in Figs. II and III. The heads 13 and the base flanges 15 of the adjoining rail sections 7 and 8 are thus effectively reinforced after customary practice in the art.

In order to reinforce the joint against lateral flexure, I form the joint bars 5 on their inner faces with longitudinal ribs 16 and 17 above and below the apertures 18 (Fig. I) for the securing bolts 19, 20 and 21, which ribs are adapted to bear directly against opposite sides of the central webs 22 of the rail sections below and above the regions of emergence of the latter respectively with the rail heads 13 and the base flanges 15. As a consequence of this constriction, it will be seen that the juncture is rendered substantially rigid against lateral flexure to better withstand side thrust induced by the wheel flanges of cars passing over the rails. For a reason which will presently appear, the upper edges 9 of the joint bars are medially recessed as at 23 and the lower edges 10 upwardly recessed as at 24 for relatively short distances inwards from opposite ends. Accordingly at these regions the joint bars are of less fishing height than the fishing height of the rails.

The provisions made for automatically compensating for wear between the heads 13 of the rail sections 7, 8 and the joint bars 5 immediately adjacent the split 6 on the rail, and between the bottom corners of said joint bars and the base flanges 15 of the rail sections are similar to those disclosed in my previous application hereinbefore referred to, and as shown, include shims 25, 26 which are made from spring metal and interposed beneath the heads 20a, 20b and 21a, 21b of the center and end bolts 20, 21. From Fig. III it will be noted that the upper ends 25a of the shims 25 are bent inwards and tapered for wedging action between the sloping under faces 12 of the heads 13 of the rail sections 7 and 8, and the counter sloped top edges of the central recessions 23 in the joint bars; while the lower edges of the said shims are curved inward slightly for fulcrum bearing at 25b upon the outer faces of the joint bars 5.

As shown in Fig. II, the shims 26 are shaped to conform with the cross sectional profile of the joint bars 5, with their lower portions extending around the flanges of the bars and terminating in tapered inward projections 26a for engaging between the upwardly recessed bottom edge portions 24 at the ends of the joint bars 5 and the rail base flanges 15. The upper portions of the shims 26 are bowed outwardly and are free of the outer faces of the joint bars 5 except for fulcrum contact at the top as at 26b. By virtue of the springiness of the shims 25, 26 and the restraint imposed upon them by the clamp bolts 20, 21, their wedge projections 25a and 26a are yieldingly urged inward and thereby automatically take up

the wear due to up and down flexure of the joint.

The bolts 19, intermediate the center and end bolts 20 and 21, are directly effective upon the joint bars 5 to clamp them firmly to the rail sections 7, 8.

From the foregoing it will be seen that my invention affords a track rail joint in which the component parts are so organized as to effectively resist and minimize wear, with attainment of a corresponding increase in the longevity of the joint and reduction in the costs of track maintenance.

Having thus described my invention, I claim:

1. In a rail joint, a pair of joint barslapping the contiguous ends of the adjoining rail sections and fitting the hollows at opposite sides thereof, said bars being formed with vertically spaced longitudinal ribs to bear against opposite sides of the vertical center webs of the rail sections, and having their lower edges upwardly recessed adjacent opposite ends; transverse clamp bolts passing through the ends of the joint bars to secure the latter to the rail sections; and spring shims interposed beneath the heads of the bolts, said shims having inward wedge projections to engage between the base flanges of the rail sections and the upwardly recessed portions of the bottom edges of the joint bars.

2. In a rail joint, a pair of joint barslapping the contiguous ends of adjoining rail sections and fitting the hollows at opposite sides thereof, said bars being formed with vertically spaced longitudinal ribs to bear against opposite sides of the vertical center webs of the rail sections and having their upper and lower edges recessed respectively at the center and at opposite ends; trans-

verse clamp bolts passing through the joint bars immediately to opposite sides of the split in the rail and also adjacent their opposite ends; and spring shims interposed beneath the heads of the several bolts, the shims associated with the intermediate pair of the bolts having inward wedge projections to engage between the heads of the rail sections and the centrally recessed portions of the top edges of the joint bars and those associated with the end bolts having inward wedge projections engaging between the base flanges of the rail sections and the recessed end portions of the bottom edges of said joint bars.

3. As a new article of manufacture, a track rail joint bar cross sectionally configured to fit the side hollows of track rails, said bar being formed with vertically spaced longitudinal ribs adapted to bear against the vertical center webs of the rails, and having a portion of its upper edge centrally recessed and portions of its lower edge at opposite ends thereof upwardly recessed.

4. In a rail joint, a pair of joint barslapping the contiguous ends of adjoining rail sections and fitting the hollows at opposite sides thereof, said bars being formed with longitudinal ribs to bear against opposite sides of the vertical center webs of the rail sections, and being at certain regions of less fishing height than the fishing height of the rails, and spring shims having wedge-shaped tongues interposed between the bars and rails at said regions, said shims being distorted from natural shape incident to the drawing together of the bars, whereby said tongues are constantly urged across the fishing spaces between the bars and rails.
